SWITCH STRUCTURE

Burton E. Shaw, Bristol, Ind., assignor to Penn Electric Switch Co., Goshen, Ind., a corporation of Iowa

Application August 29, 1938, Serial No. 227,311

7 Claims. (Cl. 200—138)

One object of my present invention is to provide a switch structure in which a plurality of switch units may be operated from a single temperature responsive element and wide range and differential adjustments are possible of being secured by my structure.

Another object is to provide a switch structure which is particularly adaptable for mounting in the bonnet of a furnace so that a temperature responsive element of the switch structure is responsive to the temperature therein and cooperates with a pair of switch units, one for controlling an air circulating fan and the other for controlling the burner system itself, such switch units being commonly called "fan" and "limit" switches respectively.

Another object is to provide a switch structure which is very sensitive to temperature changes and accurate with respect to operation at exactly the temperatures for which the various range and differential adjustments of the switch have been set.

Still another object is to provide a switch structure in which switch units including permanent magnets to secure snap action are used, the magnets also widening the differential of operation of the switch units to a substantial degree so that cams can be associated with the actuating elements of the switch units in such manner that two cams may be circumferentially adjusted relative to each other to widen or narrow the differential of operation of the switch units relative to the movement of an actuating device such as a thermostatic member and different range adjustments of the switch units can be secured by movement of the cams to different rotated positions relative to the actuating device.

Still another object is to provide a switch structure in which the element of inaccuracy with respect to the temperature responsive element and the switch unit is reduced to a minimum by the use of cams with rollers coating therewith, the rollers in turn being operable to actuate the switch units.

A further object is to provide means to eliminate the possibility of one adjustment, when being changed, effecting change of another of the adjustments of the switch structure.

A further object is to provide a switch structure in which a pair of cams may be either adjusted at the factory or adjusted on the job by a very slight change in the assembly of the switch.

A further object is to provide a switch struc-

ture including an additional cam which cooperates with an actuating cam of the switch structure to prevent undesired operation of a switch unit as a result of considerable overrun of the temperature or other condition affecting the switch structure.

Still a further object is to provide a casing for the switch structure which is so split and includes a conduit support so arranged relative to the parts of the casing as to facilitate wiring of the switch units within the casing.

With these and other objects in view, my invention consists in a construction comprising the arrangement and combination of parts shown by way of illustration in the accompanying drawings whereby the objects contemplated are attained, as hereinafter more fully set forth and pointed out in my appended claims. In said drawings:

Figure 1 is a plan view of a switch structure embodying my invention, portions of the casing being broken away and other portions thereof being shown in section.

Figure 2 is a front elevation of the switch structure showing the front or major portion of the casing removed except for one portion thereof at the lower right hand corner of the figure being shown in section.

Figure 3 is an enlarged sectional view on the line 3—3 of Figure 1 showing an adjusting means for the temperature responsive element of my switch structure.

Figure 4 is an enlarged sectional view on the line 4—4 of Figure 2.

Figures 5 to 13 inclusive are sectional views on the indicated lines 5 to 13 respectively of Figure 4, Figures 5, 7, 8 and 10 showing only the first element back of the indicated lines, Figures 6 and 9 showing only two elements back of the indicated lines, and Figures 11, 12 and 13 showing all the elements back of the indicated lines.

Figure 14 is a sectional view similar to Figure 11 showing a factory fixed adjustment; and

Figure 15 is a sectional view on the line 15—15 of Figure 1.

On the accompanying drawings I have used the reference character C to indicate generally a casing. The casing C has a shallow back portion 10 and a relatively deep front or major portion 12. Extending from the back portion 10 is a conduit support 13 in the form of a flange having a pair of conduit openings 14. The openings 14 are adapted to receive the threaded ends of conduits or BX cable fittings from which wires extend into the casing C for electrical connec-

tion with terminals 15 of switch units F and L such as fan and limit switches respectively. The major portion 12 may be secured to the back portion 10 of the casing C by clips 16 (see Figure 5 1) entering perforations 17 at one side of the casing C and a retainer screw 18 at the other side threaded in a clip 19.

Extending rearwardly from the back portion 10 of the casing C is a tubular support 20. The 10 support 20 is adapted to extend into a bonnet or plenum chamber of a hot air furnace. The support 20 is adapted to contain and support a temperature responsive element such as one of coiled bi-metal indicated as 21 on the drawings. 15 One end of the temperature responsive element 21 is secured to a bracket 22 and the other end is secured to a shaft 23.

The bracket 22 as shown in Figure 3 has an 20 arcuate slot 24 registering with a clamp screw 25. The clamp screw 25 is threaded into an ear 26 of a bracket 27. The bracket 27 is riveted as at 28 to the tubular support 20. The screw 25 may be loosened and the bracket 22 adjusted around the axis of the tube 20 to thereby adjust 25 the anchored end of the bi-metal element 21 so that a dial 29 on the outer end of the rod 23 will read directly in degrees of temperature relative to a pointer mark 30.

Rotation of the rod 23 operates the switch 30 units F and L by reason of an operative connection between the rod and the switch units as will now be described. Each switch unit as shown in Figure 15 includes an arm 31 pivoted on knife edge pivots 32 and cooperating with a leaf spring 33 to separate or engage switch contacts 34 and 35 relative to each other.

A permanent magnet 36 cooperates with an armature 37 of the switch arm 31 to effect snap action of the switch and to widen the differential 40 of the switch to a point where it requires considerable movement of an actuating element or pin 38 to move the switch from closed circuit to open circuit position or vice versa. A spring 39 is interposed between the actuating pin 38 and 45 the switch arm 31 on which there must be tension sufficiently great to overcome the pull of the magnet 36 on the armature 37 when the switch is moved from closed to the open position shown in Figure 13.

50 For operating the actuating pin 38, a roller 40 is provided which is carried by an arm 41. The arm 41 is pivoted on a pin 42 which in turn is supported in the casing C by a bracket 43. The bracket 43 also serves as a support for the fan 55 and limit switch units F and L. A comparatively heavy leaf spring 44 is connected to the arm 41 and bears against the pin 38. This spring is for the purpose of permitting movement of the arm 41 beyond any position to which the pin 38 60 might be limited without placing undue strain on the roller 40 and cams for operating it which are indicated at 45 and 46.

Thus far I have described the switch unit F. The switch unit L is of identical character and its 65 operating mechanism includes elements 40a, 41a and 44a similar to the elements 40, 41 and 44. The cams which coact with the roller 40a for actuating the switch unit L are shown at 47 and 48. I also provide an overrun cam 49 for the 70 roller 40a.

Referring to Figure 9, the cam 45 may be considered the "on" cam for the roller 40 and the cam 46 may be considered the "off" cam therefor. Dot and dash lines 50 and 51 indicate the respective distances of the periphery of the roller 40

from the center of the shaft 23 when the roller drops to "on" position during clockwise rotation of the shaft 23 and when it is raised to "off" position during subsequent counter-clockwise rotation of the shaft 23. As the shaft rotates clockwise due to an increase in temperature, the roller will first drop from the full line position to the dotted line position after passing the lobe 46a of the cam 46 and to the dash line position after passing the lobe 45a of the cam 45. Subsequently when the temperature decreases, the cam lobe 45a will engage the roller to raise it from the dash line to the dotted line position and finally the lobe 46a will engage it to raise it to the full line position. Accordingly it is obvious that the greater the distance between the lobes 45a and 46a, the greater will be the differential of 15 operation of the switch unit F.

I provide a convenient and readily settable 20 means to effect such adjustment consisting of a pair of pointers 52 and 53 which are rotatable on the shaft 23. These pointers coact with the dial 29 to indicate the temperature at which the switch F will be turned "off" or "on" respectively. To effect an operative connection between the pointer 52 and the cam 46 I provide an extension 52a on the pointer which passes through a slot 45b of the cam 45 and enters an opening 46b of the cam 46. The slot 45b is arcuate so that the cam 45 can be adjusted rotatably without interference by the extension 52a. A similar operative connection is provided between the pointer 53 and the cam 45 consisting of an extension 53a entering an opening 45c of the cam 45. 35

The pointers 52 and 53 may be locked relative to the dial 29 by a lock nut 54. The dial itself is non-rotatable on the shaft by reason of having an opening which fits the shaft, the shaft itself having flattened sides 55. The pointers 52 and 53 have circular openings so that they may rotate on the shaft. Between the pointers, a washer 56 is provided having an opening which fits the shaft whereby the washer is slidable but non-rotatable relative to the shaft. In this way 45 the adjustment of one pointer will not be transmitted to the other one when it is desirable to adjust but one of them.

Referring to Figure 11, the cam 47 is the "off" 50 cam for the limit switch L, the cam 48 is the "on" cam therefor and the cam 49 is an overrun cam therefor. In Figures 7 and 8 pointers 57 and 58 are shown for the cams 48 and 47 respectively.

Referring to Figure 9, the pointers 57 and 58 have extensions 57a and 58a. These extend through an arcuate slot 45d of the cam 45 and (see Figure 10) through an arcuate slot 46c of the cam 46. The extension 57a terminates in an opening 47a of the cam 47 while the extension 58a extends on through a slot 47b of the cam 47 and terminates in an opening 48a of the cam 48. Thereby the cam 47 is adjusted by the pointer 58 and the cam 48 is adjusted by the pointer 57. 60

The cam 48 is provided with an arcuate slot 48b in which the extended end of the extension 58a is 65 located while the overrun cam 49 is provided with an arcuate slot 49a receiving the extended end of the extension 57a. The slots 48b and 49a eliminate the necessity of the extensions 58a and 57a stopping between the faces of the cams 47 and 70 48 and between the faces of the cams 48 and 49 respectively but permit them to extend well through the cams 46 and 47 as shown by the extension 58a in Figure 2.

To prevent the movement of any one of the 75

pointers 52, 53, 57 or 58 when another one of them is being adjusted, washers 56a and 56b in addition to the washer 56 are provided. Each of these washers is slideable and non-rotatable on the shaft

- 5 23. Also the overrun cam 49 is non-rotatable on the shaft 23 and is normally held against a shoulder 23a thereof by the lock nut 54. The overrun cam 49 as shown in Figure 11 is a circumferential extension of the cam 47 so that when the cam 47 is adjusted clockwise from the position shown in Figure 11 there will still be a raised cam lobe effective to prevent return of the limit switch L to "on" position when the cam shaft 23 rotates beyond its normal degree of rotation (about 180°).
 10 15. If desired, one of the pointers 57 or 58 can be omitted and the cams 47 and 48 fixed relative to each other by a factory adjustment as shown in Figure 14. This adjustment consists of a screw 59 extending through an arcuate slot 47c of the cam 47 and screwed into a threaded opening 48c of the cam 48. The other pointer is then used merely as a range adjuster. In connection with all of the pointers, it is obvious that the range of the switches F and L can be changed since the 20 25 upper and lower limits are both adjustable so that if both are raised or lowered, the range is thereby changed while if they are spread or moved toward each other, the differential of operation is changed. I have been able to secure a wide range of both range and differential adjustment by the arrangement of cams and pointers disclosed.

Thus far I have described the operation of the switch structure with respect to the switch unit F.

- 35 30. The switch unit L operates in a similar manner from the cams 47 and 48. The on and off lobes thereof are indicated at 48d and 47d respectively and correspond to the lobes 45a and 46a. Likewise in operation the roller 40a will turn the 40 switch off when its periphery is elevated by the cam lobe 47d to a distance from the center of the shaft 23 indicated by dot and dash line 51a during clockwise rotation of the cams. The lobe 48d when it permits the roller 40a to drop into the indicated line 50a will turn the switch L on.

In some installations it is desirable to meet certain ordinances requiring that a switch structure be provided in which the fan switch F cannot be adjusted to a temperature higher than two hundred degrees. This can be accomplished by the use of a screw 60 in the dial 29 which would be sealed in position. Referring to Figures 5 and 6, the screw 60 extends to a position where the pointers 52 and 53 cannot pass it. The pointer 53 has an extension 53b to engage the screw while the pointer 52 cannot move past the pointer 53 because of being on the opposite side thereof from the screw 60.

- 60 Each of the pointers 53, 57 and 58 is provided with an extension to keep the hook end of the pointer adjacent the dial 29. These extensions are shown at 53c, 57b and 58b respectively. On the front of the casing portion 12, a window of Celluloid or the like 61 may be provided (see Figure 1) through which the dial 29 may be observed. The window 61 overlies the indicia on the dial and the pointer mark 38 on the bracket 48.

The various features described in connection with my invention all cooperate to provide a 70 switch structure which may be readily adjusted to change the range and/or differential of operation thereof. The switch is particularly adapted for operating a plurality of switch units from a single temperature or other condition responsive element.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In a switch structure, a switch having an actuating element operable to close a circuit at a first position and operable to open a circuit at a second position spaced from said first position, said switch including a permanent magnet and an armature to give snap action to the switch and to widen the differential of operation thereof whereby said first and second positions are spaced apart a substantial distance and means for operating said actuating element comprising a pair of simultaneously operable cams, a roller coating with said pair of cams, temperature responsive means for rotating said cams, one of said cams having a lobe operable to lift said roller beyond said first position as the cams rotate in one direction and the other cam having a lobe operable to drop said roller beyond said second position as the cams rotate in the opposite direction and means for changing the distance between said cam lobes in a direction circumferentially of the rotation thereof whereby to vary the differential of operation of said switch with respect to the travel of said temperature responsive means and for adjusting the position of both of said cams circumferentially of their rotation with respect to said temperature responsive means to vary the range of operation of said switch. 35

2. In a switch structure, a switch having an actuating element operable to close a circuit at a first position and operable to open a circuit at a second position spaced from said first position, said switch including a permanent magnet and an armature to give snap action to the switch and to widen the differential of operation thereof whereby said first and second positions are spaced apart a substantial distance and means for operating said actuating element comprising a pair of simultaneously operable cams, a roller coating with said pair of cams, temperature responsive means for rotating said cams, one of said cams having a lobe operable to lift said roller beyond said first position as the cams rotate in one direction and the other cam having a lobe operable to drop said roller beyond said second position as the cams rotate in the opposite direction and means for changing the distance between said cam lobes in a direction circumferentially of the rotation thereof whereby to vary the differential of operation of said switch with respect to the travel of said temperature responsive means. 50 55

3. In a switch structure, a switch having an actuating element operable to close a circuit at a first position and operable to open a circuit at a second position spaced from said first position, said switch including a permanent magnet and an armature to give snap action to the switch and to widen the differential of operation thereof whereby said first and second positions are spaced apart a substantial distance and means for operating said actuating element comprising a pair of simultaneously operable cams, a roller coating with said pair of cams, condition responsive means for rotating said cams, one of said cams having a lobe operable to lift said roller beyond said first position and the other cam having a lobe operable to drop said roller 70 75

beyond said second position, said lobes being spaced apart in a direction circumferentially of the rotation thereof whereby to require a predetermined degree of rotation of said cams between 5 said first and second positions.

4. In a switch structure, a switch having an actuating element operable to close a circuit through the switch at one position and to open a circuit therethrough at a second position, snap 10 acting means to cause the travel of said actuating element from one position to the other to be of substantial extent, temperature responsive means, cams operated thereby for operating said actuating element, one of said cams having a 15 lobe operable to move the actuating element to a position for opening said switch and the other having a lobe operable to move said actuating element to a position for closing said switch, said temperature responsive means including a rotatable shaft, said cams being rotatable thereon, a dial for indicating temperatures, a pair of pointers cooperating therewith and rotatable on said shaft, means for locking said pointers relative to said shaft, one of said cams having an arcuate slot therein, an extension from one of said pointers through said arcuate slot and entering a perforation of the other cam to position it by movement of said pointer relative to said dial and an extension from the other of said pointers 25 entering a perforation of said first cam to position it by movement of its pointer relative to said dial.

5. In a switch structure, a switch having an actuating element operable to close a circuit 30 through the switch at one position and to open a circuit therethrough at a second position, condition responsive means, cams operated thereby for operating said actuating element, one of said cams having a lobe operable to move the actuating element to a position for opening said switch and the other having a lobe operable to move said actuating element to a position for closing said switch, said condition responsive means including a rotatable shaft, said cams being rotatable thereon, a dial for indicating temperature, a pair of pointers cooperating therewith and rotatable on said shaft, means for locking said pointers relative to said shaft comprising a clamping nut for engaging said pointers with 35 each other and with said dial, one of said cams having an arcuate slot therein, an extension from one of said pointers through said arcuate slot and coacting with the other cam to position it by movement of said pointer relative to said dial, 40 an extension from the other of said pointers coacting with said first cam to position it by movement of its pointer relative to said dial, and a

washer on said shaft between said pointers, said washers being slidable and non-rotatable relative to said shaft.

6. In a switch structure, a switch having an actuating element operable to close a circuit at a first position and operable to open a circuit at a second position spaced from said first position, said switch having an inherently wide differential of operation whereby said first and second positions are spaced apart a substantial distance, and means for operating said actuating element comprising a pair of simultaneously operable cams, each having a lobe top at a substantially uniform distance from its axis of rotation, a control arm coacting with said cams, 15 temperature responsive means for rotating said cams, the lobe top of one of said cams being operable to lift said control arm beyond said first position as the cams rotate in one direction and the lobe top of the other of said cams 20 being operable to retain said control arm between said first and second positions or to drop said control arm beyond said second position as the cams rotate in the opposite direction, and means for changing the distance between said 25 cam lobes in a direction circumferentially of the rotation thereof whereby to vary the differential of operation of said switch with respect to the travel of said temperature responsive means, and for adjusting the position of both of said cams 30 circumferentially of their rotation with respect to said temperature responsive means to vary the range of operation of said switch.

7. In a switch structure, a switch having an actuating element operable to close a circuit at a first position and operable to open a circuit at a second position spaced from said first position, said switch having an inherently wide differential of operation whereby said first and second positions are spaced apart a substantial distance, means for operating said actuating element comprising a shaft, a pair of cams thereon, a control arm coacting with said pair of cams, condition responsive means for rotating said shaft, one of said cams having a lobe operable 45 to lift said control arm beyond said first position and the other cam having a lobe of uniform height to keep said control arm between said first and second positions or operable to drop said control arm beyond said second position, 50 said lobes being spaced apart in a direction circumferentially of the rotation thereof whereby to require a predetermined degree of rotation of said cams between said first and second positions.
